UNITED STATES PATENT OFFICE.

LOUIS DÉSIRÉ FRENOT, OF NEWARK, NEW JERSEY, ASSIGNOR OF ONE-HALF TO CLEMENT BERTHOUD, OF NEW YORK, N. Y.

DESIGN FOR A BREASTPIN OR SIMILAR ARTICLE OF JEWELRY.

48,175.

Specification for Design.

Patented Nov. 23, 1915.

Application filed July 14, 1915. Serial No. 39,914. Term of patent 3½ years.

To all whom it may concern:

Be it known that I, LOUIS DÉSIRÉ FRENOT, a citizen of the United States, residing at Newark, in the county of Essex and State of New Jersey, have invented a new, original, and ornamental Design for Breastpins or Similar Articles of Jewelry, of which the following is a specification, reference being had to the accompanying drawing, forming part thereof.

The figure is a plan view of a breast-pin showing my new design.

I claim:

The ornamental design for a breast-pin or similar article of jewelry, as shown.

LOUIS DÉSIRÉ FRENOT.

Witnesses:

ANTONIO ROLLERI,
AUGUST LEMINILLE.
